PAVING

Albert C. Fischer, Chicago, Ill., assignor to The
Philip Carey Manufacturing Company, a cor-
poration of Ohio

Application November 15, 1928
Serial No. 319,624

4 Claims. (Cl. 94—13)

This invention relates to surfacing units for paving structures, and particularly to a novel and improved wearing surface for planking bridges, rail crossings, sidewalks, flooring and the like, whereby the units may be held secure and prevented from creeping under traffic.

The invention consists in the features, combinations, and arrangements hereinafter described or claimed, for carrying out the above stated object and such other objects as will hereinafter appear.

The invention comprises a wearing surface composed of elastic blocks laid on a more or less rigid foundation and associated with each other or intervening strips of more rigid material to prevent creeping under the influence of traffic. Suitable units are preformed blocks or strips molded from a mixture of bitumen, rubber, or bitumen and rubber, in which a reinforcing element such as linear fibers, raw or degummed, may be incorporated and distributed throughout. Preferably the reinforcing elements are long, tough and resilient so that they are adapted to interlace and provide a supporting structure for the binder. Also within the mixture a quantity of earthy material, preferably porous, in a granular state may be distributed and housed within the interstices of the interlaced fibers. Blocks of this material are formed to interfit when adjacently laid or are laid with intervening strips which are more rigid in character. Or the blocks may be both interfitted and separated with rigid intervening strips.

In the drawing:

Figure 1 is a perspective view of a paving section embodying my invention;

Figure 2 is a perspective view of a paving section, showing a modified form of the invention; and

Figures 3—5 inclusive are similar views showing other modifications.

My invention is typified by a paving section in which elastic strips or blocks 2 and intervening rigid strips 3 are laid in a cement foundation 4, the rigid strips being constructed from wood with grooved sides 5 to interlock with tongues 6 of the elastic blocks and with adjacently poured concrete. The rigid strips may be advantageously secured to the concrete by any fastening means such as spikes 7 embedded therein. In this embodiment (Fig. 1) both types of surfacing strips are embedded directly in the foundation cement layer 4 and are of substantial depth or thickness to provide for heavy traffic.

In floor construction, sidewalks and the like, they are of much less thickness, and may be arranged without overlapping edges. Figure 2 typifies the invention in such a construction, in which foundation 8 of matched planking is laid and covered with elastic strips 9, the strips being

separated with relatively thin rigid strips 10, wood or metal, fastened to the foundation. Substantially the same structure is disclosed in Figure 4 for a paving structure in which the strips are supported on a cement foundation 11.

The embodiment in Figure 3 illustrates elastic strip 12 formed with off-set ends so that when interposed in the rigid material 4 they will be securely embedded.

Figure 5 illustrates an embodiment wherein elastic surfacing strips 13 are provided with a tongue 14 and groove 15 in opposite sides, the width of the tongue exceeding the depth of the groove so that the strips may be spaced for interposing strips 16 of more rigid material. Tie rods 75 17 may also be advantageously employed for insertion through the strips for securing them together and to the foundation.

While not indispensable, additional securing means may be inserted through the elastic and intervening rigid strips, and extended to engage the concrete or other rigid material placed beside the paving strips.

Obviously the invention is not limited to the details of the described embodiments, all of which are merely illustrative of the invention and which may be variously modified. Moreover, it is not indispensable that all features of the invention as used conjointly as certain features may be employed to advantage in various different combinations and sub-combinations.

I claim:

1. A paving structure comprising a foundation layer and preformed elastic surfacing strips embedded in the foundation to provide an elastic surfacing area, said elastic surfacing strips being interfitted and secured by a rigid strip to prevent creeping under traffic stresses.

2. A paving structure comprising a foundation layer and preformed elastic surfacing strips on the foundation, said elastic surfacing strips being laid in overlapping relation and secured by a rigid strip to prevent creeping under traffic stresses.

3. A paving structure comprising a foundation layer, elastic surfacing strips on the foundation layer laid in overlapping relation, and securing means inserted through the strips and extended to engage with adjacently laid material.

4. A paving structure comprising a foundation layer, elastic surfacing strips superposed on the foundation layer and fitted in overlapping relation, and substantially rigid strips interposed between the elastic strips adjacent the overlapping portions.

ALBERT C. FISCHER.
